COMBINATION WHISTLE, ARTICLE CONTAINER, AND COMPASS CASE, OR THE LIKE

Ralph H. Boos, Minneapolis, Minn.

Application April 14, 1951, Serial No. 14,840

Term of patent 14 years

(Cl. D34—15)

To all whom it may concern:

Be it known that I, Ralph H. Boos, a citizen of the United States, residing at Minneapolis, Hennepin County, State of Minnesota, have invented a new, original, and ornamental Design for a Combination Whistle, Article Container and Compass Case, or the like, of which the following is a specification, reference being had to the accompanying drawing, forming a part hereof.

Fig. 1 is a front perspective view of a combination whistle, article container and compass case, or the like, showing my new design;

Fig. 2 is a rear perspective view thereof; and

Fig. 3 is a front perspective view on a reduced scale of the same showing the compass case removed from the article container.

I claim:

The ornamental design for a combination whistle, article container and compass case, or the like, as shown.

RALPH H. BOOS.
